UNITED STATES PATENT OFFICE.

LEONARD DANIEL MORRIS, OF CHICAGO, ILLINOIS.

PEDAL BASS-ORGAN.

No. 870,192.

Specification of Letters Patent.

Patented Nov. 5, 1907.

Application filed October 20, 1906, Serial No. 339,813.

To all whom it may concern:

Be it known that I, LEONARD DANIEL MORRIS, a citizen of the United States, residing at Chicago, in the county of Cook and State of Illinois, have invented 5 a new and useful Pedal Bass-Organ; and I do hereby declare the following to be a full, clear, and exact description of the invention, such as will enable others skilled in the art to which it appertains to make and use the same.

- 10 My invention relates particularly to a new and automatic power organ containing all the elements of a complete instrument so that it may be used in any place and without outside assistance of any kind. Every organist finds it absolutely necessary to devote 15 a certain length of time of each day to the actual practice in the management of this instrument in order that he may acquire the desirable proficiency and skill which are indispensable in the rendition of the classical composition of the masters. The difficulty now encountered is that the ownership of a complete instrument offering an opportunity for simultaneous hand and foot practice is beyond the means of the great majority of organists, who therefore are obliged to obtain 20 permission for the use of instruments installed in 25 churches, concert halls and the like. But the use of such instruments is connected with considerable expense owing to the fact that outside means are required to operate the bellows for the purpose of furnishing wind pressure.
- 30 All these difficulties and inconveniences have been successfully overcome with the invention and construction of my pedal bass organ, the objects of which are as follows: first, to provide inexpensive means allowing the convenient practice on the pedal key board; 35 second, to combine the instrument with a piano thereby offering the possibility of a simultaneous practice for hands and feet; third, to arrange a direct mechanical connection between the keys of the pedal board and the tone controlling valves; fourth, to provide automatic means in mechanical connection with the keys 40 of the pedal keyboard for the operation of a motor and the production of power which is required to actuate wind pressure devices for the sounding of the pipes or reeds; fifth, to afford facilities so that any piano 45 may be readily attached or detached from the organ body; and sixth, to furnish the combination of a piano with a partial organ which is inexpensive, independent of surrounding conditions as regards power, which can be installed in any private dwelling, and which 50 is always ready for simultaneous hand and foot practice.

It is, of course, possible to employ auxiliary mechanical power for the operation of the wind pressure devices when such power is readily available, disconnecting and disregarding those which are directly provided for that purpose. It will also be clear that

in such case, devices other than the bellows and wind chests illustrated in the accompanying drawings, as for instance fans and blowers operated by electric, or other available power, may be used.

60

My invention is particularly useful in places where no auxiliary power for the actuation of the wind pressure apparatus is to be had, or where its application would be too expensive.

The best and most practical embodiment of my invention and the one which I preferably attach to the instrument in order to make it self contained and independent of surrounding conditions consists of the novel parts, improvements and combinations as shown in the accompanying drawings and which will herein- 70 after be fully described and claimed.

Referring to the drawings which are attached to the specification and form a part thereof, Figure 1, illustrates a sectional elevation of the structure containing the tone-controlling valve-chests and upon which the 75 pedal key board is mounted. This view also discloses the mechanical connection between the pedal keys and the power device which actuates the bellows; Fig. 2, is a plan view of Fig. 1; Fig. 3, is a detail in section, showing more fully the mechanical method employed for the manipulation of the tone-controlling valves and also the means whereby foot pressure is used to produce the necessary power for the operation of the wind devices; Fig. 4, is an end elevation of the 80 spring power motor employed for that purpose; Fig. 5, 85 is a diagram, partly in section of the bellows, the inflated wind chest, the stop mechanism controlling the wind connection between wind chest and a register of pipes or reeds, the valve chest and the pedal key board; Fig. 6, shows the construction of the pedal 90 stop action in section and the connection between the latter and the corresponding register of pipes or reeds, as shown in section at lines X—X of Fig. 7. Fig. 7, 95 is a plan view of the valve chest showing the location of the valve knobs arranged in two different chests or registers; Fig. 8, is a detail of the power winding mechanism arranged on a shaft, which is shown in section; and Fig. 9, shows a plan view of the latter. Fig. 10 is a perspective view of the organ pedestal and piano thereon.

100

Similar figures refer to similar parts throughout the several views.

The general arrangement illustrated in Fig. 1 will convey the principal idea of the embodiment of my invention. All the details of the invention are in- 105 cased in a suitable pedestal A and only the pedal key board is mounted upon the same in the separate casing B. The pipes or reeds, not shown, may be placed horizontally upon the bottom of the pedestal, or they may be arranged vertically in a structure adjacent to 110 or mounted upon the latter, as will be readily apparent and which is immaterial as regards the fundamen-

tal features of my invention. Arranged within the upper casing B and flush with the top line of the latter are the pedal keys 1 and 1' of which only one pedal key 1 is shown, although there may be a plurality of such boards; however, in illustrating the case one board is deemed sufficient for that purpose. Each key, no matter whether sharp or flat, is mounted upon the vertical pin 2 and is provided with a tapering cut-out 2' so as to allow it to freely move thereon when pressed down by the foot at the extreme opposite end. At this end each key is provided with a rigid extension 3 which passes under the cover 3' of the pedestal. Directly below each extension are located two tone controlling diaphragm valves 4, the knobs 4' of which 15 extend above the cover 5' of the valve chest 5. Upon depressing pedal key 1, its extension 3 forces the diaphragm valves 4 down; disks 4² uncover valve orifices 5² and wind passes from the interior of the valve chest 5 through wind canals 5³ into the corresponding pipe, 20 or reed, (not shown) and produces a tone.

Simultaneously with the opening of diaphragm valve 4, the rigid extension 3 depresses a vertical bar 6, and as the latter is linked with lever 7, which is rotatably mounted upon shaft 8, said lever is also pressed downward in the direction of the arrow. Upon the same shaft 8 and stationary therewith, is mounted a ratchet wheel 9. The latter is in ratchet connection with two pawls 7² movably mounted to disks 7' of lever 7 above the ratchet wheel 9. It follows that the shaft 8, 25 which is suitably journaled, will be turned in proportion with the movement of lever 7 forcing this motion. A sprocket wheel 10 is rigidly mounted at a convenient location upon shaft 8 and a chain 11 connects it with another sprocket wheel 12 secured to the winding mechanism of a spring motor 13. It will thus be seen that the foot pedal action executes two objects, first, it 30 opens the corresponding tone controlling valves 4, and second, it winds the spring of spring motor 13 so that the latter may operate the bellows 14. For this purpose a suitable link chain 15, or other power conveying means, connects the running mechanism of the spring motor 13 with crank shaft 16 and as soon as the latter revolves the bellows 14 are actuated for the purpose of furnishing the requisite wind pressure. This 35 is in short the general embodiment of my invention, from which it will be plain that this partial organ is a self-contained instrument, which can be successfully operated without any outside assistance.

I will now proceed to describe the various mechanical parts of my invention in detail.

In Fig. 3 the details of the diagram described above are more clearly shown. Only one pedal key 1 is shown which is of the full tone series in contradistinction from the series of half tone 1' as also shown in Fig. 55. 1. This key is journaled, as has been previously explained, upon the vertical pin 2 and room for movement thereon is provided by the tapering cut-out 2'. Its extreme other end carries extension 3 in rigid connection and the latter extends over the knobs 4' 60 of the corresponding tone controlling valves. The latter are of the diaphragm type 4³ being the diaphragm which closes the valve stem opening, wherein the valve stem is guided, at the top and thereby prevents any escape or waste of air. This is a very important point in organ valve construction as the air is

valuable and leaks must, in consequence thereof, be positively avoided. When key 1 is being depressed by foot power, extension 3 presses upon valve knobs 4' and forces valves 4 downward, thereby removing valve disks 4² from the orifices 5² and allowing the wind to pass from the interior of valve chest 5 through the wind connection 5³ into the corresponding sound-producing pipe or reed, not shown.

Simultaneously with the opening of the valve 4, extension 3 acts upon the vertical bar 6. The latter is 75 guided within a bracket 6' and its travel therein is limited by two pins 6². A spring 6³ restores the position of the bar to its upward limit as soon as the pressure by the extension 3 has been removed. Bar 6 is linked with lever 7 by means of a rod 6⁴, which is 80 bent at a right angle at its lower end and passed through an eye 7³ in lever 7 and held in connection therewith by means of a pin 6⁵ as shown in Fig. 9. Each disk 7', to which lever 7 is attached, is rotatably mounted upon shaft 8. This shaft is horizontally journaled 85 below the pedal keys and extends longitudinally through the pedestal so that the extension 3 of each key may act upon the corresponding vertical bar 6 and in connection therewith upon lever 7 and disk 7'. Every disk is retained in its position upon the shaft 90 by a sleeve 9' with its ratchet wheel 9. A set screw 9² secures the latter with the shaft 8. Upon the disk 7' and above ratchet wheel 9, which is face to face with the latter, are mounted two pawls 7² in ratchet engagement with ratchet wheel 9. It follows that during 95 each downward stroke of lever 7, these pawls will engage the ratchet wheel and effect a short turning movement of the shaft. Shaft 8 carries a sprocket wheel 10 in rigid connection and so located that it can be conveniently attached by a chain to the winding 100 mechanism of spring motor 13, so that, whenever shaft 8 is turned, the chain 11, which connects sprocket wheel 10 of the shaft 8 with sprocket wheel 12 of the winding mechanism, will convey this movement to the winding mechanism and turn it correspondingly. This winding mechanism consists of a revolving shaft 13' suitably mounted upon the frame plate 13² of the spring motor. Rigidly secured upon this shaft is a ratchet wheel 13³ and a pinion 13⁴. The latter is in gear connection 105 with a gear 13⁵ secured with the axle 13⁶ of spring barrel 13⁷. Above ratchet wheel 13³ and rotatably mounted upon a stationary post 13⁸ is a pawl 13⁹ in engagement with the inclined teeth of ratchet wheel 13³. It follows that at every turn of shaft 8, this movement will 110 be transferred by the chain 11 to rotary shaft 13', pinion 13⁴ will engage gear wheel 13⁵ and the spring within spring barrel 13⁷ will be wound, while ratchet wheel 13³ and pawl 13⁹ prevent its uncoiling. The spring so wound 115 actuates spring barrel 13⁷ and the teeth of the latter set the mechanism of the spring motor in motion. The running mechanism of spring motor 13 carries a suitable shaft 13¹⁰ which extends through the frame of the spring motor and which is provided with another sprocket wheel 13¹¹ for the purpose of transferring the movement of the running mechanism to a crank shaft 16 by means of chain 15 and sprocket wheel 16'. A regulator 13¹² regulates the speed of the running device of spring motor 13. This can be furthermore controlled and regulated by the action of pedal 24 shown in Fig. 2, which controls any suitable starting and stopping 120

130

mechanism (not shown). Connecting rod 14' connects the crank 16² of crank shaft 16 with a suitable bellows 14, the operation of which, when the crank is being turned, will be obvious.

5 The same shaft may be attached either to one or to a plurality of bellows as is shown in the diagram Fig. 5. It should also be stated in this connection that the method of transferring the power created by the pressure of the foot on the pedal keys may be widely 10 varied, and that, instead of using sprocket wheels and chains, a simple rope drive may be substituted. Furthermore it will also be clear that instead of using a lever 7 for each pedal key, a plurality of the latter may act upon the same lever, whereby the arrangement 15 of levers and ratchet wheels on shaft 8 may be simplified. Or the ratchet arrangement may be entirely abandoned and a friction device used.

In every organ, or partial organ, a plurality of stops is used. These stops are for the purpose of connecting 20 independent registers of pipes or reeds with the wind device. So long as the stops are undrawn, no air under pressure can enter any of the registers or valve chests 5.

The method employed for drawing the stops is shown 25 in diagram Fig. 5. In this diagram is shown a wind box 17 provided with three bellows 14 operated by the cranks 16² of crank shaft 16 and the connecting rods 14'. From this box the wind passes through pipe connection 21 into a pressure reservoir 18. The latter is provided 30 with a diaphragm cover 18' and as the chest becomes filled, it inflates the diaphragm cover and the latter rises. A uniform air pressure is obtained by placing a weight 18² upon the cover. This weight is provided with a vertical rod 18³ which passes through an orifice 35 in the cross strap 18⁴ for guidance. 18⁵ is a safety valve, which is opened by contact of the valve stem 18⁶ with cross strap 18⁴ as soon as the chest is fully inflated and the surplus air is allowed to escape.

In valve chest 19 the various stop valves are housed. 40 Connection 21' conveys the wind under pressure into this chest and its further progress is here barred unless one or more of the stops are drawn. These stops are conveniently placed within the reach of the feet of the player and consist of a pedal 20, journaled at point 20' 45 and held in its position by spring 20². When a certain stop is to be drawn, the pedal 20 is forced down and passed under an offset 20³ in the wood work of the casing as shown in Fig. 6. In forcing the pedal into this position, it depresses diaphragm stop valve 22; the disk 22' 50 of the latter uncovers orifice 22² and wind under pressure is allowed to enter through connection 21² into the valve chest 5 in which are located the tone-controlling valves for a definite register of pipes or reeds. In Fig. 6 is shown a number of tone controlling valves of a certain register, of which one is illustrated in the opened or active position. The extension 3 by means of which these valves are opened is shown in section above the valve knob 4. These valves are shown on lines X—X, X—X of the plan view of a valve chest containing two 55 registers of pipes or reeds. All of the diaphragm valves 4, as well as the stop valves 22 are retained in their closed position by springs 23, so that when the pressure is removed from the pedal and the latter is pulled back into its normal position by its individual spring, each 60 valve will move back and close the corresponding valve 65

orifice. In order to guide the movement of the valves, each lower end of the respective valve stem fits into a round indentation in the corresponding valve spring at point 23.

As has been explained, this invention is principally 70 for the purpose of affording means for foot practice as well as for the rendition of music, and if no sound is wanted, it is not necessary to wind the spring motor. It will therefore be obvious that many different means may be employed to disengage the shaft 8 from the 75 spring motor during that time, for which purpose a friction clutch or the like—not shown—may be successfully used. When it is desired to practice with both the feet and hands the piano C is mounted upon the pedestal as shown in Fig. 10.

80

For the rendition of music the spring motor is wound as soon as the foot practice upon the pedal key-board is started. The running mechanism of the spring motor is started by pedal 24 and the wind bellows 14 force a certain volume of air into the wind reservoir 18 until 85 the latter becomes fully inflated when the surplus of air will be discharged through safety valve 18⁵. From this reservoir the wind passes into the stop valve chest 19 and through the corresponding drawn stop action into the valve chest 5 containing the tone-controlling 90 valves of a definite register of pipes or reeds. It will thus be seen that the object of making this instrument self contained and entirely independent of surrounding conditions as regards power has been successfully accomplished.

95

Having now fully described my invention what I claim as new and desire to secure by Letters Patent is:—

1. The combination with an organ having pedal keys, of a piano mounted on said organ and adapted to be operated simultaneously with said keys, wind generating means in said organ, a motor adapted to actuate said wind generating means and means operated by the pedal keys adapted to supply energy to the motor.

100

2. In a device of the class described the combination with pedal keys, of valves actuated thereby, wind generating means, a spring motor adapted to operate the same and mechanism adapted to automatically wind said motor when the keys are operated.

105

3. In a device of the class described the combination with pedal keys, of valves actuated thereby, bellows adapted to generate wind for said valves, a spring motor, winding mechanism therefor and means operatively connecting said pedal keys with the winding mechanism and adapted to operate the same when the keys are operated.

110

4. In an organ, the combination with pedal keys of diaphragm valves actuated thereby, a wind generating device, a motor adapted to operate the same and means operated by the pedal keys adapted to supply energy to the motor.

115

5. In an organ, the combination with valves, of pedal keys each having a rigid extension thereon adapted to open a corresponding valve when the pedal is depressed, a bellows adapted to supply wind to said valves, a motor adapted to operate the bellows and means operated by the keys for transmitting energy to said motor.

120

6. In an organ, the combination, of pedal keys, with valves, a rigid extension on each pedal key adapted to open a corresponding valve when the pedal key is depressed, a vertical bar 6 adapted to be pressed downward by the downward movement of the pedal key, a lever 7 connected by means of a joint with the said vertical bar, a shaft 8 upon which the lever 7 is rotatively mounted, a ratchet wheel 9 secured to said shaft 8, a disk on said lever, pawls 7² mounted upon the disk and in ratchet connection with said ratchet wheel, a sprocket wheel 10 mounted upon the shaft 8 and rigidly secured thereto, a spring motor 13, a winding mechanism for said motor, a

125

130

135

- sprocket wheel 12 and a chain 11 adapted to convey the rotary movement of the shaft 8 to the winding mechanism, a bellows adapted to be operated by said motor and means for conveying the wind from the bellows to said valves. 45
- 5 7. In an organ, the combination of pedal keys, with valves, means on said keys adapted to open said valves when the keys are depressed, a bellows, wind connections between the bellows and said valves, a spring motor adapted to operate said bellows and means connected with each 10 pedal key adapted to wind the motor when the keys are operated. 50
8. In an organ, the combination with pedal keys of valves operated thereby, a shaft journaled beneath said keys, means operated by each key adapted to rotate said 15 shaft, a spring motor, winding means therefor operatively connected with said shaft, a bellows driven by said motor and means for conveying wind from said bellows to said valves. 55
9. In an organ, the combination of pedal keys, with 20 valves, means connected with said pedal keys adapted to open one of said valves whenever the corresponding pedal key is depressed, a shaft journaled beneath the keys, means actuated by said keys adapted to rotate the shaft, a bellows adapted to supply wind to the valves, a motor adapted to operate said bellows and means operatively 25 connected with said shaft for energizing the motor. 60
10. In an organ, the combination with pedal keys, of valves, means connected with the said pedal keys adapted to open one of said valves whenever the corresponding 30 pedal key is depressed, a rotative shaft, means actuated by said keys adapted to rotate the shaft, a spring motor 13, a spring winding mechanism thereon, means connected with said shaft and adapted to operate said winding mechanism, a bellows operated by the motor and means for conveying wind from the bellows to said valves. 65
11. In an organ, the combination of pedal keys, and a rigid extension 3 secured on each, with valves adapted to be opened by said extension 3, a shaft 8, means adapted to rotate said shaft when the pedal keys are depressed, a 35 70 spring motor 13, a spring winding mechanism on said motor, means adapted to transmit the movement of said shaft to the spring winding mechanism to actuate the latter, a sprocket wheel 13¹¹ attached to the motor, a wind generating bellows 14, a crank shaft 16 and connecting rod 14' operating said bellows, a sprocket wheel 16' secured to the said crank shaft 16, means adapted to connect the sprocket wheel 13¹¹ with the sprocket wheel 16' conveying the movement of the mechanism in said spring motor 13 to said crank shaft 16 and operating the bellows. 75
12. In an organ, the combination with pedal keys, of valves, a shaft 8 adapted to be rotated, means connected with said keys and adapted to actuate said valves and said shaft simultaneously, a motor 13, means whereby the said movement of the shaft is adapted to operate said motor, a wind generating bellows 14, and means connecting said motor with the wind generating bellows and actuating the latter. 80
13. In an organ, the combination with pedal keys, of valves operated thereby, a shaft, means connecting each key with said shaft and adapted to rotate the same; a motor 13, means actuated by said shaft adapted to operate the motor, a wind generating bellows 14, operated by said motor, a wind reservoir 18, wind connection between said bellows 14 and reservoir 18, a stop action chamber 19, diaphragm stop valves therein, a pedal stop 20, wind connection between said reservoir and said stop action chamber, a valve chest 5 containing the valves 4, and wind connection between said stop action chamber and the corresponding valve chest. 85
14. In an organ, the combination with pedal keys, of valves, means adapted to actuate said valves when the corresponding pedal key is depressed, a motor 13, devices interposed between said motor and said pedal keys adapted to actuate said motor when each pedal key is depressed, a bellows actuated by said motor, a stop action chamber 19, a wind connection between said bellows and said chamber, a reservoir 18 interposed in said connection, a plurality of valve chests 5 and wind connection between the said stop action chamber and the corresponding valve chest. 90
- In testimony whereof I have signed my name to this specification in the presence of two subscribing witnesses.
